UNITED STATES PATENT OFFICE.

GEORG SEIBT, OF BERLIN-SCHONEBERG, GERMANY.

ELECTRIC DISCHARGE TUBE.

Application filed August 26, 1921, Serial No. 495,504, and in Germany October 24, 1913.

(GRANTED UNDER THE PROVISIONS OF THE ACT OF MARCH 3, 1921, 41 STAT. L., 1313.)

It is known that an ionized gas may under suitable conditions serve for detecting, amplifying or generating alternating currents: known examples are the Fleming 5 valve, the De Forest audion, the Poulsen arc and the Lieben tube.

According to this invention the freed ions are caused to pass through a double grid, screen or the like. The stream of ions 10 may thus be easily controlled and may produce considerable amplification.

The invention is illustrated by the accompanying drawings, in which like parts are similarly designated, and in which—

15 Figure 1 illustrates diagrammatically a vacuum tube constructed in accordance with my invention.

Fig. 2 shows a modification.

20 Fig. 3 illustrates the application of an auxiliary potential connected to one of the grids.

In a vacuous glass vessel is arranged a filament F heated by a small battery A. From the filament pass negative ions which 25 traverse the grid or screen G¹, G² before reaching the metal plate M. T is a telephone, J a galvanometer and H an auxiliary battery. The wires a, b, connected to the grid G¹ lead to the circuit whose oscillation is to be detected or amplified. The 30 metal plate M has in it slots which correspond to the spaces between the two combs G¹, G² of the grid and in this instance the grid M forms part of or also acts as anode.

35 If the spaces between the combs are exactly opposite the slots in grid M, the greater portion of the stream of ions proceeding from F will pass through the plate M and only a few will impinge on the metal 40 of M. If, however, a difference of potential be applied at a, b, the electric field between G¹, G², will deflect the stream of ions at right angles to its previous direction.

The consequence is that a greater portion 45 of the stream of ions falls upon the plate M and a smaller portion passes through the slots.

If on the other hand the slots in M are exactly opposite the teeth of the grid G¹, G², 50 nearly the whole stream of ions which pass the grid will fall upon the plate M and only when the grid is electrically excited will the greater portion pass through the slots.

It will be seen from the foregoing that

the grid G¹, G², possesses the properties of 55 a valve by which the stream of ions between F and M is controlled.

Figure 2 shows another modification.

In this in rear of the grid M a solid metal plate V is provided. 60

In considering the action of this arrangement we must distinguish between the case in which the spaces between the combs G¹, G², are opposite to the slots and the case in which they are opposite the strips of the 65 grid M. In the first case, on the excitation of the combs G¹, G² the stream of ions which reaches V decreases; in the second case it increases. It is in general better to work with a decrease of the stream of ions. 70

The sensitiveness of the arrangement can under some circumstances be considerably increased if at the combs G¹, G², as shown in Figure 3, an auxiliary potential is applied which is preferably variable. Obviously the stream of ions can by this means be so deflected that it passes through the grid M in the most favourable form. In practice such favourable conditions cannot be exactly suited by the manufacture of the 75 arrangement. The said auxiliary potential is preferably employed for regulating the formation of the stream. 80

In the foregoing arrangements it has been assumed that the deviation of the stream of 85 ions resulted from an electrical field. As is known magnetic forces act in the same manner and the alteration of movement is at right angles to the magnetic field and the original direction of the stream of ions. 90

If, for example, a coil through which a current is passing be moved over the tube the ions emitted from the heated wire are deflected in a peripheral direction. 95

I claim:

1. In a discharge tube in which an ionic stream passes from one point to another; a bi-part, ion-deflecting screen and a slotted plate, both in the path of the ionic stream. 100

2. In a discharge tube in which an ionic stream passes from one point to another, a bi-part, ion-deflecting screen and a slotted plate in the path of the ionic stream, and another plate beyond the slotted plate. 105

3. In a vacuum tube, a filament sending out an ionic stream, means for conducting off the said ionic stream, a grid traversed by said stream, a second grid impinged by

the said stream after having passed said first grid, means for controlling the passage of the ions through the said two grids, and means for applying an auxiliary potential to the parts of the said ion-deflecting grids for regulating the formation of the ionic stream, said grids lying in different planes.

4. In a discharge tube, a heated element, a bi-part grid and a second grid, spaced 10 and successively arranged.

5. In a discharge tube, a heated element, a bi-part grid, a second grid and a plate arranged successively and spaced from one another, the electrons passing from said element successively to the two grids and then 15 to the plate.

6. In a discharge tube, a heated element, a plurality of grids arranged in spaced succession, one of said grids being a bi-part 20 grid, and means to deflect the ion-stream leaving the latter grid.

7. In a discharge tube, a heated element, a bi-part grid, a second grid and a plate, and means to deflect the ion-stream leaving the bi-part grid. 25

8. In a thermionic vacuum tube, a cathode arranged to be heated, a plurality of grid-like electrodes arranged in spaced and substantially parallel planes.

9. In a thermionic vacuum tube, a cathode and a plurality of grid-like electrodes the spaces in one grid corresponding substantially to the spaces in the other grid. 30

10. In a thermionic vacuum tube, a cathode, a two-part grid, and a second grid, arranged in succession, and means to maintain a potential difference between the parts of the two-part grid. 35

In testimony whereof I have signed this specification.

DR. GEORG SEIBT.
